UNITED STATES PATENT OFFICE

GEORGE W. CHARETTE, OF LEMON GROVE, CALIFORNIA

AEROPLANE LANDING

Application filed October 18, 1930. Serial No. 489,682.

This invention relates to a runway or aeroplane landing, the primary object of the invention being to provide means to permit the landing of aeroplanes in cities, or 5 other restricted places, with facility.

An important object of the invention is to provide a device of this character which will provide a wide elevated landing surface, sufficiently wide to permit of a safe landing, 10 and an inclined runway extending from the landing surface.

Another object of the invention is to provide guiding means at the sides of the track or runway, to guide the aeroplanes over the 15 landing surface and runway.

With the foregoing and other objects in view, which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without 25 departing from the spirit of the invention.

Referring to the drawings:

Figure 1 is a side elevational view of a device constructed in accordance with the invention.

30 Figure 2 is a plan view thereof.

Figure 3 is an enlarged rear elevational view of the device.

Figure 4 is a sectional view though the surface of the runway.

35 Referring to the drawings in detail the device comprises a substantially wide landing surface 5 merging into a runway 6.

Supporting members 7 support the device, the height of the supporting members 7 being 40 such that the wide landing surface will be supported above the roofs or building tops to permit aeroplanes to land without interference of the houses or buildings.

The supports for the runway section 6, 45 vary in height so that the runway will be inclined at a proper angle to permit the aeroplanes to gravitate to the bottom thereof. Extending in parallel relation with the side edges of the landing surface and runway, are vertical guide plates 8, the guide

plates being of heights to guide the aeroplane passing over the device, by the contact of the wheels of the running gear, therewith.

Braces 9 are secured to the device, and have connection with the guide plates 8, to 55 support the guide plates in their proper positions, and at the same time brace the plates against lateral movement, caused by the striking of the wheels of an aeroplane, thereagainst.

The reference character 10 designates lateral guiding members that have their forward ends curved inwardly at 11, where they connect with the channel bar 12, that extends throughout the length of the runway. The 65 width of the channel bar 12, is such as to provide a guide for the back wheel of the running gear of an aeroplane, so that the aeroplane will be automatically guided over the runway.

Owing to the construction of the device, it will be obvious that large or small aeroplanes may be landed on the landing surface, the construction of the guiding plates and channel bar being such that running 75 gears of wide or narrow gauge may be guided by the contact of the wheels with the plates.

It will of course be understood that while the landing surface will be located over the 80 tops of houses or buildings, the runway will be so positioned that aeroplanes passing thereover will be guided to a building or station from which passengers may be loaded or unloaded.

85 I claim:

1. A landing device for aeroplanes, comprising a wide landing surface merging into a narrow inclined runway, means for supporting the landing surface an appreciable 90 distance above the ground surface, a central guiding member extending throughout the length of the wide landing surface and runway, said central guiding member being substantially wide at one of its ends.

95 2. A landing device for aeroplanes comprising an elevated wide landing surface, a runway, said landing surface merging into the runway, guide plates extending in parallel relation with the edges of the wide 100

landing surface and runway, to guide an aeroplane moving thereover, a central guiding member comprising a channel bar, extending throughout the length of the runway and landing surface, and one end of the channel bar being widened to guide a wheel to the center thereof.

3. A landing device for aeroplanes, comprising a landing surface and runway, a central guiding member extending over the landing surface and runway and one end of the guiding member being wide to engage the tail skid of an aeroplane to guide the tail skid and aeroplane over the landing surface.

In testimony that I claim the foregoing as my own, I have hereto affixed my signature.

GEORGE W. CHARETTE.
